UNITED STATES PATENT OFFICE.

LESLIE DANA, OF ST. LOUIS, MISSOURI, ASSIGNOR TO CHARTER OAK STOVE & RANGE COMPANY, A CORPORATION OF MISSOURI.

OVEN VENTILATOR.

Application filed December 15, 1926. Serial No. 154,981.

The present invention relates to oven ventilators and aims to improve generally such devices by providing a simple, reliable and efficient automatic regulator suitable for 5 maintaining a desired temperature condition within an oven.

Furthermore, the invention aims to provide means for manually adjusting the ventilator of an oven according to the conditions 10 desired to be maintained within it, combined with an automatic thermostat control for varying the adjustment as temperature conditions within the oven are varied.

Further aims and advantages of the invention appear hereinafter in connection with the description of the embodiment of the invention selected for illustration and shown in the accompanying drawings, wherein

Fig. 1 is a rear elevation of an oven door 20 with my invention applied thereto, part of the lining thereof being broken away more clearly to show the ventilator adjusting and control mechanism;

Fig. 2 is a vertical sectional view, taken 25 on the line 2—2 of Fig. 1, of my improved ventilator combined with an oven door;

Fig. 3 is a horizontal sectional view of the same, taken on the line 3—3 of Fig. 1, the dotted lines showing the ventilator in open 30 position, and

Fig. 4 is a fragmentary front elevation of a portion of an oven door showing the ventilator.

In the illustrative embodiment of the invention shown in the drawings, an oven casting, herein illustrated as an oven door 10, is provided with an opening 11 forming a seat for a closure member 12, as for instance a damper, which is adjustable to vary the 35 size of the opening between it and the door 10 so as to regulate the amount of hot air permitted to escape from the oven and cool outside air admitted to take its place. The oven door 10 has preferably formed on the 40 rear face thereof, a plurality of lugs 13, threaded to receive suitable fastening elements, as for instance screws 14, for attaching a protecting and ventilating lining member 16 to the rear of the oven door 10.

The lining member 16 is formed with upper and lower rows of openings 17, providing passages for circulation of air from the oven between the lining and the door, by permitting the ingress of cold air into the 45 bottom and the egress of hot air from the

top of the oven when the closure 12 is adjusted inwards away from its seat 11 in the door 10, and thereby ventilating and cooling the oven.

A guide bar 18 preferably is formed on or 60 secured to the rear face of the closure 12, and has portions extending laterally beyond the closure for engagement over guide pins 19 carried by the inner rear face of the door 10, for guiding the closure in its movement toward and away from the door 10 and preventing rotation of the closure about its axis.

A thermostatic element 20, herein illustrated as a bimetallic bar composed of a plurality of flat, flexible, metallic strips having different coefficients of expansion, is secured at one end to the door, preferably to a suitable lug 15, and, at the opposite end, directly engages the closure 12, or bar 18, 70 to which it may be secured. The thermostat bar 20 constitutes a spring tension element for normally holding the closure 12 tightly against its seat 11 in the oven door 10; and suitable means, as an adjusting screw 21, 75 may be provided to vary the tension of the bar and adjust it to start to open the closure at the temperature desired.

My invention further contemplates the provision of means for manually adjusting the position of the closure 12 with reference to its seat 11 according to the normal condition desired to be maintained within the oven, as for instance, for "hot", "medium" 80 and "slow" cooking. According to the illustrated embodiment, a spindle 22 is journaled in the closure member 12 and has secured to its outer end a handle 23 and pointer 24. The inner end of the spindle carries a follower 25 adapted to ride upon the inclined faces of cam members 26, formed upon the rear face of the oven door 10 and preferably arranged circumferentially around the opening or closure seat 11. As shown in the drawings, two such cam members are provided, on diametrically opposite sides of the opening 11, and the extremities of the follower 25 engage like portions of the cam surfaces, whereby to maintain the closure 90 centrally disposed with respect to the center of the opening in any of its adjusted positions.

The front face of the closure 12 preferably bears suitable indicating indicia 27, to indicate various temperature or cooking condi- 100 105 110

tions desired to be maintained within the oven, as for instance, "Hot", "Med" and "Slow" as shown in Fig. 4. The cam members 26 are preferably provided with notches 28 at symmetrically spaced points upon their inclined faces corresponding with the positions of the indicia 27, so designed that when the handle 23 is turned to move the pointer 24 to one of the indicia 27, the follower 25 will be turned to engage in the corresponding notches upon the inclined faces of the cam members 26, and thereby move the closure and its adjusting mechanism, as a unit, inwardly against the tension of the spring 13 thermostat bar to open the damper and hold it securely in partly or fully opened position, as desired. Thus cold outside air may enter through the opening 11 and thence through the lower row of openings 17 in the lining 16, and simultaneously hot air may escape from the oven through the upper row of openings 17 and out through the opening 11. Thus a circulation of air is established in the oven tending to cool the oven proportionately to the size of the space between the closure 12 and its seat 11.

The opening thus formed (see dotted lines Fig. 3) between the closure 12 and the seat 11 is also adjustable automatically to control the amount of circulation. Should the oven increase in temperature beyond that which is desired to be maintained, the thermostat bar will be flexed inwardly, moving with it the closure 12, and thus increase the size of the space between the closure and its seat 11 and consequently the circulation of air. As the oven is thereafter cooled by reason of the increased circulation of air through it, the thermostat bar tends to straighten out to return the closure to its original adjusted position.

Advantages of my improved oven ventilator and control reside in its adaptability to a large variety of heating ovens. It is efficient in its operation and provides for a ready adjustment of the oven and an automatic control for maintaining the oven at the adjusted temperature condition. Furthermore, it is simple in construction, reliable in operation and not easily broken or deranged.

Obviously my invention is not restricted to the details of construction shown or described.

55 I claim:

1. The combination of an oven door casing having a ventilating opening therein, closure means for controlling the circulation of air through said opening and oven, manually actuated means accessible from the exterior for positioning the closure means with reference to said opening according to the temperature desired to be maintained within the oven, and means for automatically varying the position of the closure means

from its originally adjusted position according to deviations of temperature conditions within the oven from the condition desired to be maintained.

2. The combination of an oven door casing 70 having a ventilating opening communicating with said oven, closure means movably mounted for cooperation with said opening and adapted to regulate the circulation of air therethrough, manually actuated means accessible from the exterior for adjusting the position of said closure means with reference to said opening, according to the temperature desired to be maintained within the oven, and temperature responsive means for automatically moving said closure means relatively to said opening to vary the circulation of air to cool the oven, responding to temperature changes within the oven in excess of the condition desired to be maintained therein.

3. The combination of an oven door casing having a ventilating opening therein, and enclosing a space communicating with said oven, closure means mounted for movement relatively to said opening and adapted to regulate the circulation of air therethrough, manually actuated means accessible from the exterior for adjusting the position of said closure means toward or from said opening, according to the temperature desired to be maintained within the oven, and temperature responsive means for automatically moving said closure means away from the opening and from its normally adjusted position, to increase the circulation of air to cool the oven, responding to temperature changes within the oven in excess of the condition desired to be maintained therein.

4. The combination of an oven door casing 105 having a ventilating opening therein communicating with said oven, closure means mounted for movements to close or open said openings to the outside air, manually actuated means accessible from the exterior for positioning said closure means to close said opening or to be spaced therefrom according to the temperature condition desired to be maintained within the oven, and temperature controlled means for automatically moving said closure member away from its adjusted position proportionately to the change in temperature conditions within the oven in excess of the condition desired to be maintained, whereby to increase the circulation of air through the opening to cool the oven to the desired temperature condition.

5. The combination of an oven door casing 125 having a ventilating opening therein, and communicating with said oven, closure means mounted for movement relatively to said opening and adapted to regulate the circulation of air therethrough, manually actuated means accessible from the exterior 130

for adjusting the position of said closure means toward or from said opening, according to the temperature desired to be maintained within the oven, and temperature controlled means for automatically moving said closure means away from the opening and from its normally adjusted position, to increase the circulation of air to cool the oven, according to temperature changes within the oven in excess of the condition desired to be maintained therein, said temperature controlled means being operative automatically to return said closure means to its original adjusted position as the temperature of the oven approaches the condition desired to be maintained in the oven.

6. The combination of an oven door casing having an opening, a closure therefor, said opening and closure constituting a passage for the circulation of air through the oven, variable at the will of the operator, means accessible from the exterior for varying the size of the passage, according to temperature condition desired to be maintained in the oven, and temperature responsive means for automatically varying the size of the passage according to variations in the temperature condition of the oven from the desired oven temperature, thereby to maintain the temperature condition of the oven approximately at the desired temperature.

7. The combination of an oven door having an opening, a closure therefor, said opening and closure constituting a passage for the circulation of air variable at the will of the operator, an oven door lining carried by said door and provided with ventilating openings therein, manually controlled means accessible from the exterior for varying the size of said passageway for proportionately varying the circulation of air through the oven according to the temperature condition desired to be maintained in the oven, and temperature controlled means for automatically varying the size of the passage proportionately to the variations in temperature from the desired temperature of the oven.

8. The combination of an oven door having an opening therein, closure means for said opening, cam means formed on the inner face of said door near said opening, and manually operative means journalled in said closure means including a handle and a cam follower, said follower being in contact with said cam members, the arrangement being such that rotation of the handle and follower causes said follower to ride upon said cam and move the closure members away from the opening.

9. The combination of an oven door having a ventilating opening therein constituting a seat for a damper, a damper for said opening, cam means having an inclined face on the rear face of said door adjacent said opening, and a manually adjustable cam fol-

lower journalled in said damper adapted to be rotated so that as the follower rides upon the inclined face of the cam, the damper will be proportionately spaced from said opening.

10. The combination of an oven door having an opening therein forming a seat for a damper, a damper mounted for cooperation with said seat, said damper and seat constituting a variable passage for the circulation of air to and from the oven, means under the control of the operator for varying the size of the passage according to the temperature condition desired to be maintained in the oven, said means including cam members having inclined faces on the rear face of the door, and a cam follower rotatably journalled in said damper adapted to engage the inclined faces of said cam members thereby to move the damper toward and away from its seat.

11. The combination of an oven door having an opening therein forming a seat for a damper, a damper yieldingly mounted for cooperation with said seat, said damper and seat constituting a variable passage for the circulation of air to and from the oven, means under the control of the operator for varying the size of the passage according to the temperature condition desired to be maintained in the oven, said means including cam members having inclined faces on the rear face of the door, and a cam follower rotatably journalled in said damper adapted to engage the inclined faces of said cam members thereby to move the damper toward and away from its seat.

12. The combination of an oven door having an opening therein forming a seat for a damper, a damper mounted for cooperation with said seat a variable passage for the circulation of air to and from the oven, means for supporting and yieldingly urging the damper against its seat, means under the control of the operator for varying the size of the passage according to the temperature condition desired to be maintained in the oven, said means including cam members having inclined faces on the rear face of the door, and a cam follower rotatably journalled in said damper adapted to engage the inclined faces of said cam members thereby to move the damper toward and away from its seat.

13. The combination of an oven door having an opening therein forming a seat for a damper, a damper mounted for cooperation with said seat, and constituting with said seat a variable passage for the circulation of air to and from the oven, a thermostat bar composed of a plurality of metallic strips having different coefficients of expansion for supporting and yieldingly urging the damper against its seat, means

under the control of the operator for varying the size of the passage according to the temperature condition desired to be maintained in the oven, said means including cam members having inclined faces on the rear face of the door, and a cam follower rotatably journaled in said damper adapted to engage the inclined faces of said cam members thereby to move the damper toward and away from its seat.

14. The combination of an oven door having an opening therein forming a seat for a damper, a damper mounted for co-operation with said seat, and constituting with said seat a variable passage for the circulation of air to and from the oven, the front face of said damper bearing suitable indicia, means for supporting and yieldingly urging the damper against its seat, means under the control of the operator for varying the size of the passage according to the temperature condition desired to be maintained in the oven, said means including cam members having inclined faces on the rear face of the door, and a cam follower and pointer rotatably journaled in said damper, and connected for movement in unison, the follower being adapted to engage the inclined faces of the cam members, and the pointer being adapted to be moved across the front face of said damper selectively in line with one of the indicia, the arrangement being such that movement of the follower upon the faces of the cam members, corresponding to the movement of the pointer, moves the damper proportionately away from its seat thereby to regulate the circulation through the oven.

15. The combination of an oven casing having a ventilating opening therein, closure means for controlling the circulation of air through said opening and oven, manually actuated means accessible from the exterior for positioning the closure means with reference to said opening according to the temperature desired to be maintained within the oven, said means preventing closing of said

opening but permitting further opening thereof, and means for automatically varying the position of the closure means from its originally adjusted position according to deviations of temperature conditions within the oven from the condition desired to be maintained.

16. The combination of an oven casing having a ventilating opening communicating with said oven, closure means movably mounted for cooperation with said opening and adapted to regulate the circulation of air therethrough, manually actuated means accessible from the exterior for adjusting the position of said closure means with reference to said opening, according to the temperature desired to be maintained within the oven, said means preventing closing of said opening but permitting further opening thereof, and temperature responsive means for automatically moving said closure means relatively to said opening to vary the circulation of air to cool the oven, responding to temperature changes within the oven in excess of the condition desired to be maintained therein.

17. The combination of an oven door having an opening therein, closure means for said opening, a thermostat bar for supporting said closure means and normally holding it in position to close said opening, said thermostat bar flexing with raise in temperature to move said closure means away from said opening, cam means formed on the inner face of said door near said opening, and manually operative means journaled in said closure means including a handle and a cam follower, said follower being in contact with said cam members, the arrangement being such that rotation of the handle and follower causes said follower to ride upon said cam and move the closure members away from the opening.

In testimony whereof, I have signed my name to this specification.

LESLIE DANA.
